(57) **CLAIM**

We claim the ornamental design for a tooth for a circular saw or a mower drum, as shown and described.

DESCRIPTION

FIG. 1 is a perspective view of a tooth for a circular saw or a mower drum according to a first embodiment of the present design;

FIG. 2 is a top view of the tooth for a circular saw or a mower drum of FIG. 1, the bottom view being an identical view thereof;

FIG. 3 is left side view of the tooth for a circular saw or a mower drum of FIG. 1, the right side view being an identical view thereof;

FIG. 4 is rear view of the tooth for a circular saw or a mower drum of FIG. 1;

FIG. 5 is a front view of the tooth for a circular saw or a mower drum of FIG. 1;

FIG. 6 is a perspective view of a tooth for a circular saw or a mower drum according to a second embodiment of the present design;

FIG. 7 is a top view of the tooth for a circular saw or a mower drum of FIG. 6, the bottom view being an identical view thereof;

FIG. 8 is left side view of the tooth for a circular saw or a mower drum of FIG. 6, the right side view being an identical view thereof;

FIG. 9 is rear view of the tooth for a circular saw or a mower drum of FIG. 6;

FIG. 10 is a front view of the tooth for a circular saw or a mower drum of FIG. 6;

FIG. 11 is a perspective view of a tooth for a circular saw or a mower drum according to a third embodiment of the present design;

FIG. 12 is a top view of the tooth for a circular saw or a mower drum of FIG. 11, the bottom view being an identical view thereof;

FIG. 13 is left side view of the tooth for a circular saw or a mower drum of FIG. 11, the right side view being an identical view thereof;

FIG. 14 is rear view of the tooth for a circular saw or a mower drum of FIG. 11;

FIG. 15 is a front view of the tooth for a circular saw or a mower drum of FIG. 11;

FIG. 16 is a perspective view of a tooth for a circular saw or a mower drum according to a fourth embodiment of the present design;

FIG. 17 is a top view of the tooth for a circular saw or a mower drum of FIG. 16, the bottom view being an identical view thereof;

FIG. 18 is left side view of the tooth for a circular saw or a mower drum of FIG. 16, the right side view being an identical view thereof;

FIG. 19 is rear view of the tooth for a circular saw or a mower drum of FIG. 16;

FIG. 20 is a front view of the tooth for a circular saw or a mower drum of FIG. 16;

FIG. 21 is a perspective view of a tooth for a circular saw or a mower drum according to a fifth embodiment of the present design;

FIG. 22 is a top view of the tooth for a circular saw or a mower drum of FIG. 21, the bottom view being an identical view thereof;

FIG. 23 is left side view of the tooth for a circular saw or a mower drum of FIG. 21, the right side view being an identical view thereof;

FIG. 24 is rear view of the tooth for a circular saw or a mower drum of FIG. 21; and,

FIG. 25 is a front view of the tooth for a circular saw or a mower drum of FIG. 21.

The broken lines form no part of the design and are for illustrative purposes only.
